US0D1077269S

(12) **United States Design Patent** (10) **Patent No.:** **US D1,077,269 S**
(45) **Date of Patent:** **** May 27, 2025**

(54) **SAMPLE COLLECTOR**

- (71) Applicant: **Zhejiang Orient Gene Biotech Co., Ltd.**, Huzhou (CN)
- (72) Inventors: **Lili Shen**, Huzhou (CN); **Jianqiu Fang**, Huzhou (CN); **Fangli Zhou**, Huzhou (CN)
- (73) Assignee: **ZHEJIANG ORIENT GENE BIOTECH CO., LTD.**, Huzhou (CN)
- (**) Term: **15 Years**
- (21) Appl. No.: **29/888,747**
- (22) Filed: **Apr. 4, 2023**

(30) **Foreign Application Priority Data**

- Feb. 27, 2023 (CN) 202330075950.0
- (51) **LOC (15) Cl.** 24-02
- (52) **U.S. Cl.** USPC **D24/216**
- (58) **Field of Classification Search**
USPC D24/216, 217, 222–224, 226, 229, 231, D24/169, 130, 133

(57) **CLAIM**

The ornamental design for a sample collector as shown and described.

DESCRIPTION

FIG. 1 is a first perspective view of a sample collector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a second perspective view thereof;

FIG. 9 is a third perspective view thereof;

FIG. 10 is a perspective view of the sample collector in use; and,

FIG. 11 is another perspective view of the sample collector in use with a cap removed.

The broken lines depict the environment structure that form no part of the claimed design.

1 Claim, 11 Drawing Sheets
